UNITED STATES PATENT OFFICE.

HENRY W. STAPLES, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

BATTERY HAND LAMP.

Application filed April 30, 1927. Serial No. 187,771.

This invention relates to battery hand lamps of the type including a casing for the battery, a lamp bulb with a suitable reflector in one end of the casing and an end glass or lens for enclosing and protecting the bulb and reflector. The present invention relates more particularly to means for retaining, supporting and centering the end glass or lens in the end of the hand lamp over the reflector and lamp bulb.

Hand lamps of the type described are usually provided with tubular or cylindrical battery casings, and the reflector surrounding the lamp bulb is ordinarily inserted in one end of the casing, being retained in place by a suitable flanged retaining band. The end glass or lens is clamped between the flange of the retaining band and the end of the casing or the reflector, and thus both the lens and the reflector are secured in place by means of this retaining band. When it is desired to replace or remove the lamp bulb or the reflector, the retaining band must be removed from the end of the casing, and the end glass or lens which is normally held in place by the flange of this band is then likely to fall out and become broken. As the end glasses or lenses employed in hand lamps of the type described are usually beveled or curved on their outer surfaces, it has been found difficult to center such glasses with respect to the retaining band, the curved outer surface permitting the glass to slip with respect to the flange on the band and so to assume a slightly eccentric position with respect to the band.

With the above and other considerations in mind, it is proposed in accordance with the present invention to provide a hand lamp having a flanged lens retaining band embodying means for removably securing the end glass or lens therein, and, more specifically, it is proposed to provide a lens retaining ring which releasably cooperates with the retaining band to secure the end glass or lens thereto and to center the glass within the band.

It is a further object of the invention to provide a retaining means of the type described which is simple in construction, inexpensive and highly effective.

Other specific objects, advantages and characteristic features of the invention will

become apparent from the detailed description thereof.

In describing the invention in detail, reference will be made to the accompanying drawings, in which;

Figure 1 is a view of the blank from which the retaining ring of the present invention is struck;

Fig. 2 is an inner end view of the lens retaining ring;

Fig. 3 is a sectional view of the ring, taken along the line 3—3 of Fig. 2;

Fig. 4 is a side view of the retaining ring together with the end glass, showing the relative positions of these parts;

Fig. 5 is a side view of the flanged lens retaining band with the end glass and retaining ring in place therein;

Fig. 6 is a sectional view, taken along the line 6—6 of Fig. 5, and viewed in the direction of the arrows; and

Fig. 7 is a side view, partly in section, of a portion of a hand lamp with the end glass secured thereto by the retaining means of the present invention.

Referring to the drawings, the lens retaining means of the present invention is shown in connection with a tubular or cylindrical hand lamp having an enlarged reflector and end glass, it being understood that the invention is equally applicable to many other types of lamps. Referring to Fig. 7, the hand lamp shown comprises a battery casing 1 having an enlarged end compartment 2 within which is located a reflector 3 of suitable shape, surrounding a lamp bulb 4. The casing 1 contains the usual battery or other source of energy for the lamp 4 and is preferably provided with a suitable switch for controlling the flow of current through the lamp bulb, but as these means form no part of the present invention, and are well known to those skilled in the art, they will not be described herein.

The outer end of enlarged portion 2 of the casing 1 is preferably threaded and provided with a rounded inturned flange 5, the reflector 3 having a flange 6 which rests on the flange 5 and is clamped in engagement therewith by the lens retaining means as hereinafter described.

An end glass or lens retaining band B is provided having a cylindrical portion 7

which is screw threaded as shown whereby this band may be secured to the enlarged end 2 of the casing 1. An inturned flange 8 is provided on the band B, this flange being preferably flared to conform with the outer beveled or curved surface of an end glass or lens. The band B may be formed in any suitable shape, and as shown, is provided with an octagonal edge portion 9 to facilitate removal of the band from the casing. Any suitable type of lens or end glass may be employed, and in the embodiment shown, an end glass 10 having plane surfaces and beveled edges is provided.

Referring now more particularly to the end glass retaining ring R, shown in detail in Figs. 1 through 4, this ring is preferably formed of comparatively thin resilient sheet metal, and has an internal diameter substantially equal to the inside diameter of the flange 8 on the band B. The ring R is broken or cut along a radial line 11, and is provided at its outer edge with a plurality of equally spaced end glass retaining lugs 12, extending outwardly substantially at right angles to the ring R. The lugs 12 are preferably formed integral with the ring R, being struck, pressed or cut therefrom in any suitable manner. A plurality of inwardly extending rounded ears 13 are provided on the outer edge of the ring R at points equally spaced from adjacent lugs 12, the ears 13 being preferably formed integral with the ring R. The ears 13 are bent at an angle to extend outwardly from the edge of the ring R as shown in Fig. 3.

When it is desired to secure the end glass 10 within the band B, the glass is first placed within the band with the bevel of the glass resting on the flared flange 8 as shown in Figs. 5 and 7. The retaining ring R is then slightly compressed and placed within the cylindrical portion 7 of the band B with the lugs 12 toward the end glass. The ring R extends within the octagonal portion of the band B, the lugs 12 engaging the outer edges of the glass 10 and the ears 13 resting on the ledge formed by the octagonal portion 9, as clearly shown in Figs. 5 and 7. In this manner, the glass 10 is securely clamped within the band B. The band B may then be secured to the casing 1, the reflector 3 being clamped against the flange 5 of the casing by the engagement of the ring R with the outer surface of the flange 6. The lugs 12 serve to center the end glass 10 in the band B, while the ears 13 securely clamp the glass in engagement with the flange 8 on the band. Due to the break 11 in the ring R, this ring is readily adaptable to slight variations in the diameters of the lenses or end glasses employed, the ring being easily expandable to accommodate lenses having diameters larger than the diameter defined by the lugs 12 when the ring is in

the contracted condition as shown in Fig. 2.

When it is desired to remove the glass 10 from the band B for cleaning or other purposes, the ring R may be removed by lifting one end thereof adjacent the break 11 therein and compressing or contracting the ring whereby the ears 13 are withdrawn from the portion 9 of the band. The ring and glass may then be readily removed from the inner end of the band.

From the description given, it will be readily apparent that the lens retaining device of the present invention is simple in construction, inexpensive and forms an effective means for removably securing a lens or end glass within a flanged retaining band or casing.

Although the retaining means of the present invention has been disclosed and described in connection with a single specific type of hand lamp and end glass, it is obvious that this retaining means is equally applicable to other types of lamps, lenses and cover glasses, and it should be understood that various changes and modifications may be made in the form of the retaining means without departing from the scope of the invention as defined by the appended claims.

I claim:

1. The combination of a lamp casing having an opening therein, a flanged lens retaining band surrounding said opening and removably secured to said casing, a lens within said band engaging the flange thereof, a flat resilient ring within said band, spaced lugs on said ring for engaging the edges of said lens and spaced ears extending from the outer edge of said ring for releasably engaging the interior of said band, whereby said lens is retained within said band and is centered with respect to said band.

2. The combination of a lamp casing having an opening therein, a flanged circular end glass retaining band removably secured to said casing and surrounding said opening, a circular end glass within said band engaging the flange thereof, a flat circular ring of resilient sheet material within said band lying parallel to and in engagement with the inner plane surface of said glass, said ring having a break therein, and a plurality of separate means on said ring for respectively engaging the edge of said glass and the interior of said band, whereby said ring is secured within said band.

3. In a hand lamp, in combination with a battery casing having an opening therein, a flanged circular end glass retaining band removably secured to said casing and surrounding said opening, a circular end glass within said band engaging the flange thereof, a flat circular ring of sheet material lying parallel to and in engagement with the inner plane surface of said glass, a plurality of spaced lugs on the outer edge of said ring extending

toward the flange of said band and engaging the edge of said glass, and a plurality of spaced ears on the outer edge of said band between said lugs extending backward from said flange and engaging the interior of said band.

4. The combination of a lamp casing having an opening therein, a flanged lens retaining band surrounding said opening and 10 removably secured to said casing, a lens within said band engaging the flange thereof, a flat circular ring lying parallel to and in engagement with the inner plane surface of said lens, a plurality of spaced lugs on said 15 ring extending at right angles thereto at the outer edge thereof and engaging the edge of said lens, and a plurality of spaced ears on said ring between said lugs extending substantially at right angles to said ring and en- 20 gaging said band.

5. The combination of a lamp casing hav-

ing an opening therein, a flanged end glass retaining band surrounding said opening and removably secured to said casing, a circular end glass within said band en- 25 gaging the flange thereof, a flat circular ring having a break therein and lying parallel to and in engagement with the inner surface of said glass, a plurality of spaced lugs integral with said ring at the outer edge 30 thereof and extending toward said opening in engagement with the edge of said glass, and a plurality of spaced ears integral with said ring at the outer edge thereof and extending inwardly from the plane of said 35 ring for engaging the interior of said band, whereby said glass is centered with respect to said opening by said lugs, and the ring and glass are retained within said band by said ears. 40

In testimony whereof I affix my signature.

HENRY W. STAPLES.

CERTIFICATE OF CORRECTION.

Patent No. 1,664,905.

Granted April 3, 1928, to

HENRY W. STAPLES.

It is hereby certified that error appears in the printed specification of the above numbered patent requiring correction as follows: Page 2, lines 102 and 103, claim 1, strike out the words "extending from the outer edge of"; same claim line 102, after the word "ears" insert the word "on"; line 117, claim 2, after the word "separate" insert the word "spaced", and after the word "means" strike out the word "on" and insert the words "extending from the outer edge of"; page 3, line 3, claim 3, for the word "ears" read "ears"; and that the said Letters Patent should be read with these corrections therein that the same may conform to the record of the case in the Patent Office.

Signed and sealed this 8th day of May, A. D. 1928.

(Seal)

M. J. Moore,
Acting Commissioner of Patents.
